UNITED STATES PATENT OFFICE.

GUSTAV DENTSCH, OF VIENNA, AUSTRIA-HUNGARY.

APPARATUS FOR INTRODUCING STEAM INTO CENTRIFUGAL MACHINES.

SPECIFICATION forming part of Letters Patent No. 744,503, dated November 17, 1903.

Application filed August 28, 1903. Serial No. 171,053. (No model.)

To all whom it may concern:

Be it known that I, GUSTAV DENTSCH, a subject of the Emperor of Austria-Hungary, residing at Vienna, in the Province of Lower Austria and Empire of Austria-Hungary, have invented a new and useful Improvement in Apparatus for Introducing Steam into Centrifugal Machines for Whitening Sugar, of which the following is a specification.

10 My invention relates to apparatus by means of which steam is introduced into the baskets of centrifugal machines for separating the molasses from the sugar crystals leaving the vacuum-pan. As is well known, it is desirable that steam used for this purpose should be perfectly dry, so as to render the molasses more fluid rather by heating it than by diluting it, as otherwise too much sugar would be dissolved.

15 My invention therefore has for its main object to provide apparatus by means of which perfectly-dry steam can be obtained with certainty.

The special arrangement and construction 25 of my apparatus is based upon the fact that dry steam is by wiredrawing it converted into steam of less pressure and lower temperature, in which, however, the loss of pressure is more considerable than the loss of temperature, so that the resulting steam is of 30 higher temperature than would correspond to its pressure and that consequently this steam is superheated steam, which is capable to spend a certain amount of heat without undergoing condensation.

According to my invention a steam-drier combined with a wiredrawing-valve is interposed between the steam-main and the steam-spraying nozzle arranged in the basket of the 40 centrifugal machine, and this nozzle is also adapted to wiredraw the steam.

The invention also comprises certain features of the piping carrying the nozzle and the bluing device interposed into the said 45 piping.

In the annexed two sheets of drawings, Figure 1 is a sectional elevation of a centrifugal machine provided with my improved apparatus for introducing steam. Fig. 2 is a top 50 view of the said centrifugal and apparatus. Fig. 3 is a sectional elevation of the combined steam-drier and wiredrawing-valve. Fig. 4

is a section on line 4 4 of Fig. 3. Fig. 5 is a top view of the joint of the piping carrying the steam-spraying nozzle. Fig. 6 is a section 55 on line 6 6 of Fig. 5. Fig. 7 is an elevation of the bluing device interposed into the piping carrying the steam-spraying nozzle. Fig. 8 is a section on line 8 8 of Fig. 7. Fig. 9 is a sectional elevation of the steam-spraying nozzle, and Fig. 10 is a cross-section of the same on line 10 10 of Fig. 9.

Referring to Figs. 1 and 2, 1 is a pipe controlled by a stop-valve, through which steam is conveyed from the steam-main. (Not shown 65 in the drawings.) The steam enters the combined steam-drier and wiredrawer inclosed in the casing 2 2' and thence passes through the joint 3 4 into the pipe 5 and through the casing 6 of the bluing device into the downwardly-extending pipe 7, which carries the steam-spraying nozzle 8. The pipe 9 extends from a cock 10 at the bottom of the casing 2 into the casing 11 of the centrifugal in order to discharge into the same a mixture of condensed water and steam.

In the construction of the combined steam-drier and wiredrawer it was made a point, as far as possible, to utilize the heat of the live steam and to avoid by all means held out by 80 techniques the losses of heat by conduction and by radiation.

It will be seen from Fig. 3 that the casing 2 2' of the combined steam-drier and wire-drawing-valve is composed of two parts 2 and 2' in order to admit of the inner parts being inserted; but owing to the large surfaces of contact at the joint the casing behaves like a solid piece under the point of view of conduction of heat. Moreover, it is provided with 85 an insulating-coating. The lower part 2 of the casing is provided with a neck 12, by means of which the casing is connected with the steam-pipe 1. As shown in Fig. 1, the shell of the cock 10 is cast in one piece with 90 the bottom of part 2 of the casing 2 2'. However, the said bottom may also be provided instead with a screw-threaded hole 13 (shown in Fig. 3) and destined to have a neck of the said cock-shell screwed into it. Into this 100 lower part 2 of the casing of the steam-drier and wiredrawer is inserted a hollow cylinder 14, closed at its bottom and having its flanged top screwed into a corresponding screw-

threaded seat formed in the part 2 of the casing, while the outer surface of the hollow cylinder 14 carries a broad thin helical rib or screw-thread 15, tightly fitting into the part 5 2 of the casing. By the said helical rib 15 a helical passage is formed, the lower portions of which communicate through slots 16 with the inner hollow space of the cylinder 14. The steam flowing in through the neck 12 10 rushes through this helical passage, and thereby has a whirling movement imparted to it, in consequence of which the particles of water which it contains are by the centrifugal force thrown against the outer sides of the 15 passage. The dry steam passes through the slots 16 and rises within the hollow cylinder 14, while the separated water flows downward along the helical rib or partition 15 and gathers in the lowermost portion of the 20 casing. Thence it escapes through the partly-opened cock 10 with a certain quantity of steam into the casing 11 of the centrifugal.

Above the top flange of the hollow cylinder 14 a disk 17 is tightly screwed into the part 2 25 of the casing 2 2', the said disk 17 being pierced by radial slots and serving as a valve-face for a disk-shaped valve 18, provided with corresponding slots and kept in position by the upper part 2' of the casing. The circular 30 valve 18 is provided with a stem 19, which projects to the outside through a stuffing-box 20 and carries a handle 21, by means of which the valve 18 can be turned upon its valve-face 17, the movement being limited by a 35 stop-pin 22, screwed into the valve-face and projecting into a recess 23 of the edge of the valve 18. The lower portion of the said valve-stem 19 is made solid and provided with radial ribs, which promote the exchange of 40 caloric between the highly-heated valve-stem and the surrounding wiredrawn steam of lower temperature. The top portion 24 of the said valve-stem is made tubular in order to admit of the insertion of a thermometer.

45 When the apparatus is working, the valve 18 is so adjusted upon its valve-face 17 as more or less to narrow the slots through which the dry steam is obliged to flow, and thereby the said steam is withdrawn, and consequently 50 converted into superheated steam of less pressure and lower temperature. A cock 25, having a neck of its shell screwed into a screw-threaded hole 26 of the upper part 2' of the casing of the steam-drier and wiredrawer 55 near the exit-neck 27 of the said casing, admits of samples of steam being examined. According to the nature of the samples and the readings of the thermometer the position of the circular valve 18 is conveniently adjusted.

The neck 27 is connected with the flanged neck 28 of the pipe-section 3 of a hollow hinge-joint, which comprises a second short section of pipe 4, carrying a neck 29 and having its 60 open end projecting into a stuffing-box 31, formed at the end of the pipe-section 3. Both short pipe-sections 3 and 4 are closed at the

outer ends, and they are held together by a bolt 30 and nuts 32.

The neck 29 of the hollow hinge-joint 34 is 70 connected with a pipe 5, running to the shell 6 of the bluing device, which is used when the color of yellowish products is to be improved. The bluing device, of which Figs. 7 and 8 are detail views, essentially consists of an elbow 75 33, cast in one piece, with the ultramarine-holder 6 tightly closed by the screwed cover 34, the middle portion of which is made up into a stop-cock shell 35, round which the cover is dished out. The hollow plug 36 of the stop-cock can be turned by means of the handle 37. It will be readily understood that when the plug 36 is so adjusted that the slots 38 of the plug and the shell register ultramarine solution poured into the dished-out cover 34 80 85 will flow into the holder 6. Below the bottom of the said ultramarine-holder 6 another stop-cock shell 39 is formed, the hollow space of which communicates with the ultramarine-holder through the short passage 40 and 90 95 9c through a passage 41, bored in the rib of the side of the holder 6 and nearly extending to the top edge of the said holder. In the same vertical plane with the short passage 40 the stop-cock shell 39 is pierced by a hole into 100 which a short pipe 42 is inserted, the said pipe having its free end projecting into the elbow 33 and bent downward so as to form a spout. In a similar manner as the pipe 42 corresponds to the short passage 40 a passage 43, also opening into the elbow 33, corresponds to the long bore 41, and the plug 44 of the stop-cock is provided with two notches 45, by means of which the passages 41 and 43, on the one hand, and 40 and 42, on the other hand, can be 105 110 brought into communication at the same time, the plug 39 being operated by means of the handle 46. Through the passages 43 and 41 steam gets to the surface of the ultramarine solution in the holder 6 and causes drops of 115 120 125 the solution to fall down from the pipe 42, when these drops are carried along by the steam.

By means of the lower flange 47 the described bluing device rests on the two-parted lid 48 of the casing 11 of the centrifugal machine, and when one-half of this lid is removed the pipe 5 with the bluing device 6, the pipe 7, and the steam-spraying nozzle 8 may be swung upward, as indicated in dotted lines in Fig. 1, and free access got to the basket of the centrifugal machine for withdrawing the whitened sugar.

130 Into the screw-threaded lower end of the elbow 33 screws the steam-pipe 7, carrying the steam-spraying nozzle 8. It forms a characteristic feature of my invention that I so construct this nozzle as to enable it again to wiredraw the steam, and thereby to make its dryness certain, although it may have 135 been impaired by losses of caloric on the way through the pipe 5, bluing device 6, and pipe 7.

It will be seen from Figs. 9 and 10 that the

free end of the nozzle has a portion 49 of larger diameter and that the edge of this portion is turned out conical. To the conical valve-seat thus formed corresponds a valve 8, having its hollow stem 50 screwed into the portion of the nozzle behind the widened end portion, so that by further screwing home or partly unscrewing the valve 8 one may adjust the width of the narrow conical slot between the valve-body and valve-seat.

That portion of the hollow valve-stem 50 which is located within the widened portion 49 of the nozzle has apertures 51 cut through its sides. The steam passes through the apertures 51 into the annular space of the portion 49 and thence escapes through the narrow conical slot, whereby it is wiredrawn anew.

What I claim as my invention, and desire to secure by Letters Patent, is—

1. In apparatus for introducing steam into centrifugal machines for whitening sugar, the combination with the steam-spraying nozzle located in the basket of the centrifugal machine and the pipe supplying steam to the said nozzle of an apparatus for drying and wiredrawing the steam, the said apparatus being interposed into the supply-pipe of the nozzle, substantially as and for the purpose described.

2. In apparatus for introducing steam into centrifugal machines for whitening sugar, the combination with the steam-spraying nozzle located in the basket of the centrifugal machine and the pipe supplying steam to the said nozzle of an apparatus for drying and wiredrawing the steam, the said apparatus being interposed into the supply-pipe of the nozzle, and the nozzle being adapted to wire-draw the steam flowing through it, substantially as and for the purpose described.

3. In apparatus for introducing steam into centrifugal machines for whitening sugar, the combination with the centrifugal, the steam-spraying nozzle located in the basket of the same, and the steam-supply pipe of the nozzle, of an annular chamber provided with a helical partition and having the steam-supply pipe opening into its top, a pipe connecting the bottom end of the annular chamber with the casing of the centrifugal, a stop-cock adapted to control this pipe, openings in the lower portion of the inner side of the annular chamber, a wiredrawing-valve arranged in the central space surrounded by the annular chamber, a passage connecting the top end of the said central space with the steam-supply

pipe, and means for controlling the wire-drawing-valve by hand, substantially as and for the purpose described.

60

4. In apparatus for introducing steam into centrifugal machines for whitening sugar, the combination with the centrifugal, the steam-spraying nozzle, and its steam-supply pipe of a hollow hinge-joint interposed into the steam-supply pipe, the portion of piping between the hinge-joint and the nozzle being elbow-shaped and the downwardly-extending branch carrying a projection resting on the lid of the centrifugal, substantially as and for the purpose described.

65

5. In apparatus for introducing steam into centrifugal machines for whitening sugar, the combination with the steam-supply pipe of a cylindrical spout, a widened end portion of the said spout, a conical valve-seat formed at the end of the said widened portion, a corresponding valve having its hollow stem screwed into the spout, and steam-ports cut through the sides of the hollow valve-stem, substantially as and for the purpose described.

70

6. In apparatus for introducing steam into centrifugal machines for whitening sugar, the combination with the steam-spraying nozzle and its steam-supply pipe of a closed ultramarine-holder mounted upon the said pipe, a passage leading from the top portion of the inner space of the holder into the steam-pipe, a second passage leading from the bottom portion of the holder into the said pipe, and a stop-cock adapted simultaneously to control both passages, substantially as and for the purpose described.

75

7. In apparatus for introducing steam into centrifugal machines for whitening sugar, the combination with the steam-spraying nozzle and its steam-supply pipe of a closed ultramarine-holder mounted upon the said pipe and having a dished-out cover, a stop-cock 100 shell made integral with the said cover, a plug inserted into the shell and adapted to be operated by hand, a passage leading from the top portion of the holder into the steam-pipe, a passage leading from the bottom portion of 105 the holder into the steam-pipe and means for controlling both passages, substantially as and for the purpose described.

80

In witness whereof I have signed this specification in presence of two witnesses.

GUSTAV DENTSCH.

Correction in Letters Patent No. 744,503.

It is hereby certified that the name of the patentee in Letters Patent No. 744,503, granted November 17, 1903, for an improvement in "Apparatus for Introducing Steam into Centrifugal Machines," was erroneously written and printed "Gustav Dentsch," whereas the said name should have been written and printed *Gustav Deutsch*; and that the said Letters Patent should be read with this correction therein that the same may conform to the record of the case in the Patent Office.

Signed and sealed this 9th day of February, A. D., 1904.

[SEAL.]

F. L. ALLEN,
Commissioner of Patents.
